(Cl. D70—1)

Fig. 1.

Fig. 2.

Fig. 3.

Fig. 4.

Fig. 5.

Fig. 1 is a perspective view of a sewing machine looking toward the front and head-end of the machine and showing the design in accordance with this invention.

Fig. 2 is a rear elevational view.

Fig. 3 is a top plan view.

Fig. 4 is a head-end elevational view.

Fig. 5 is a standard-end elevational view.

The characteristic feature of the design resides in the provision of a bracket arm having a ledge longitudinally of the front face of the bracket arm parallel to the lower extremity thereof, and being extended across the

top portion of the standard and curved into the end face of the standard, substantially as shown.

I claim:

The ornamental design for a sewing machine, substantially as shown and described.
